US0D1028619S

(12) **United States Design Patent** (10) Patent No.: **US D1,028,619 S**
(45) Date of Patent: ** May 28, 2024

(54) **STAND MIXER**

(71) Applicant: **WHIRLPOOL CORPORATION**,
Benton Harbor, MI (US)

(72) Inventors: **Amy Sarah Beisiegel**, Berrien Springs,
MI (US); **Brandon Tyler Mock**, St.
Joseph, MI (US); **John Jay Myers**,
Saugatuck, MI (US); **Katie Remaly**, St.
Joseph, MI (US)

(73) Assignee: **WHIRLPOOL CORPORATION**,
Benton Harbor, MI (US)

(**) Term: **15 Years**

(21) Appl. No.: **29/822,955**

(22) Filed: **Jan. 13, 2022**

(51) LOC (14) Cl. **31-00**

(52) U.S. Cl.

USPC **D7/412; D7/376**

CLAIM

The ornamental design for a stand mixer, as shown and described.

DESCRIPTION

FIG. 1 is a perspective view of a stand mixer according to the design;

FIG. 2 is a front elevation view thereof;

FIG. 3 is a back elevation view thereof;

FIG. 4 is a right side elevation view thereof;

FIG. 5 is a left side elevation view thereof;

FIG. 6 is a top plan view thereof; and,

FIG. 7 is a bottom plan view thereof.

Broken lines are environmental only and form no part of the claimed design.

1 Claim, 7 Drawing Sheets
